UNITED STATES PATENT OFFICE.

PAUL AGRILLO, OF CHICAGO, ILLINOIS, ASSIGNOR OF ONE-HALF TO ABE GOLDSHOLL, OF CHICAGO, ILLINOIS.

LINK BELT.

Application filed July 29, 1925. Serial No. 46,874.

This invention appertains to the manufacture of strips or belts formed from a plurality of different sections or links whereby small sections of material can be used to 5 form an attractive appearing belt capable of use for different purposes, such as fan or other drive belts, garment supporters and the like.

The primary object of the invention is to 10 provide a belt formed from a plurality of links which will be easy to assemble and which will lie substantially flat and be exceptionally strong in use.

Another object of the invention is to 15 provide such a belt, in which the sections or links thereof are so formed, as to interlock with one another and thereby preclude the accidental separation of the links even prior to the finishing of a complete belt.

20 A still further object of the invention is to provide a belt of the above character, which will be efficient in use, one that will be simple and easy to manufacture and one which can be placed upon the market at an 25 extremely low cost and which will present an attractive and pleasing appearance.

With these and other objects in view, the invention consists in the novel construction, arrangement and formation of parts, 30 as will be hereinafter more specifically described, claimed and illustrated in the accompanying drawings; in which drawings:

Figure 1 is a plan view of a series of links connected together to form a fragment of the belt.

Figure 2 is a longitudinal section through the same taken on the line 2—2 of Figure 1, and

Figure 3 is a plan view of one of the 40 links open.

The belt embodies a plurality of like links 80 each of which include an elliptical body 81, a semi-ovoid shaped tab 82 and a connecting link 83. The body portions 81 of 45 the links are provided with transversely extending equi-distantly spaced outer and inner slots 84 and 85, respectively, and an elongated opening 86 which connects the said slots 84 and 85 together. The slots 84 and 85 extend laterally in both directions 50 beyond the opening 86. The tab 82 is provided with a transversely extending slot 87. In the formation of the belt, one link is used as the terminal link and the tab 82 is 55 folded over the body 81 until the slot 87

registers with the inner slot 85. The next link is then taken and forced through the alined slots 87 and 85 by folding the tab 82 longitudinally after which the tab is straightened out and folded on the neck 83 60 on the body 81 until its slots 87 registers with the outer slot 84 in the master link. A third link is now taken and its tab is inserted through the alined slots 87 and 85 of the second link and through the slot 65 84 of the master link. Other links are added in the same manner until the desired length of belt or chain is formed. The provision of the opening 86 serves as means for permitting the ready assembling of the links 70 and allows the tabs to readily be placed through the desired slots.

While I have described the principle of the invention together with the structure which I now consider to be the best embodiment thereof, I desire to have it understood that the structure shown is merely illustrative and that such changes may be made therein when desired as are within the scope 75 of the invention as claimed. 80

What I claim as new is:

1. A belt comprising a terminal link consisting of an elliptical shaped body, a semi-ovoid shaped tab having a constricted neck, the body being provided with a pair of spaced transversely extending slots and an elongated opening connecting the slots together, the tab being provided with a single transversely extending slot, the tab being folded at the neck over the body portion 90 to aline the slot therein with the innermost slot of the body, a second similarly formed link arranged through the alined slots of the first link and folded over to aline the slot of its tab with the innermost slot of 95 its body and to arrange its alined slots in alignment with the outermost slot of the terminal link for receiving a third and similarly formed link.

2. A belt comprising links each having a 100 body provided with inner and outer slots, a tab underlying the body and having a slot registering with the inner slot, and a neck connecting the body and tab, the registering slots of one link registering with the 105 outer slot of another and the necks of the links passing through the registering slots.

3. A belt comprising links each having a body provided with inner and outer slots and with an opening located between and 110

communicating with the slots, a tab underlying the body and having a slot registering with said inner slot, and a neck connecting the body and tab, the registering slots of one link registering with the outer slot of another and the necks of the links passing through the registering slots.

4. A belt comprising links each having a body provided with inner and outer slots and with an opening located between and communicating with the slots, the slots ex-

tending laterally in both directions beyond the opening, a tab underlying the body and having a slot registering with said inner slot, and a neck connecting the body and tab, the registering slots of one link registering with the outer slot of another and the necks of the links passing through the registering slots.

In testimony whereof I affix my signature.

PAUL AGRILLO:
